Primary Examiner—Robert M. Spear*Assistant Examiner*—Susan Bennett-Hattan(74) *Attorney, Agent, or Firm*—Knoble Yoshida & Dunleavy, LLC(57) **CLAIM**

The ornamental design for a “tamper-evident band,” as shown and described.

DESCRIPTION

FIG. 1 is a perspective view showing our new design;

FIG. 2 is a front elevational view;

FIG. 3 is a rear elevational view;

FIG. 4 is a top plan view;

FIG. 5 is a bottom plan view;

FIG. 6 is a cross-sectional view taken along lines 6—6 in FIG. 5; and,

FIG. 7 is a cross-sectional view taken along lines 7—7 in FIG. 6.

Any broken lines in the drawings depict probable environment only and form no part of the claimed design.
